UNITED STATES PATENT OFFICE

2,531,680

VIBRATOR FOR THE FILLINGS OF TOOTH CAVITIES

Gösta Karl Gustaf Gustafson, Göteborg, Sweden,
assignor to Västra Sveriges Dentaldepot, Göteborg, Sweden

Application July 28, 1948, Serial No. 41,127
In Sweden July 9, 1947

7 Claims. (Cl. 32—54)

1

The present invention relates to an apparatus for imposing vibratory impacts upon fillings of tooth cavities, and the object of the invention is to provide an improved construction of an apparatus suitable for the purpose in consideration.

I attain this object by mechanism illustrated in the annexed drawing, in which Fig. 1 shows a portion of an angularly extending handle of a type known per se for boring tools, said handle having provided therein a contrivance according to the invention; Fig. 2 shows a pin adapted to operate upon the fillings; Fig. 3 is an endwise view of the same pin viewed from above in Fig. 2; and Fig. 4 shows a further embodiment of the apparatus according to the invention.

In the drawing, 1 designates an angularly extending handle of a type known per se, such as is generally used when drilling in teeth. Extending through the handle is a driving shaft 2 formed at the end thereof with teeth 3 adapted to engage teeth 4 on a sleeve 5 arranged at right angles to the shaft 2. The sleeve 5 is rotatably mounted in a hollow within the front portion of the handle.

Detachably secured to the handle by means of screw-threads is a socket 6, the one end of which, being located in the hollow of the handle, serves as a thrust bearing for the sleeve 5 to prevent unintentional removal of the latter from the hollow. The opposite end of the socket 6 is formed with cams or similar members 7 adapted to engage corresponding cams 8 on a member 9 mounted in the sleeve 5. The member 9 is secured to a pin 10 adapted to operate upon fillings in tooth cavities, and the cams 7, 8 are adapted to displace the pin in the axial direction during the rotary movement thereof. The rotation of the pin 10 is mediated by the shaft 2 through the agency of the sleeve 5—with which the pin is non-rotatably connected—for instance by the pin being provided with a shoulder 11 cooperating with a corresponding shoulder in the bore of the sleeve 5. The pin is adapted to be detachably connected to the handle in a manner known per se with the aid of a locking bar 12, which may grasp about a restriction 13 in the upper end portion of the pin. The bar 12 is pivotally mounted in a slit provided in the handle.

The contrivance operates in the following manner. If the shaft 2 is caused to rotate, the sleeve 5 and thus the pin 10 will also rotate. By reason of the fact that the member 9 provided with the cams 8 is rigidly connected with the pin 10, the member 9 is caused to participate in the rotary movement of the pin, the cams 8 being thus caused to run over the cams 7 on the socket 6.

2

Now, when the outer end of the pin is pressed against the filling intended to be operated upon, a vibratory movement is brought about, inasmuch as the pin will be displaced back and forth for short distances on account of the cams 7 and 8 and the pressure exerted by the operator on the pin.

In the form of embodiment shown in Fig. 4, the pin 14, with the aid of which the fillings are operated upon, is non-rotatably arranged in a sleeve 15, which is in turn non-rotatably connected with the handle 1. The upper end of the pin 14 located within the sleeve 15 is formed with a conical head 16 engaging a corresponding recess at the center of a circular disc 17. The head 16 also forms a shoulder 18 having one end of a spring 19 bearing thereagainst, said spring tending to move the pin toward the disc 17. The axial displacement of the pin 14 is effected by 10 means of cams or similar members 20 on the disc 17, said cams being adapted to cooperate with similar cams 21 on a socket 22 secured to the handle. The disc 17 is rotatably arranged, and to this end it is secured to the end of a shaft 23 20 adapted to be driven in a similar manner as that portion of the pin 10 (Fig. 1) which is located within the hollow of the handle.

The mode of operation of the apparatus now described is substantially the same as that of the previously described contrivance. It should be noted in this connection that the spring 19 may also be adapted to move the disc 17 in a direction toward the socket 22, so that the cams 20 and 21 will always engage each other without the necessity of pressing the pin 14 manually inwardly.

Obviously, the constructive design of the invention is not limited to the forms of embodiment herein described and illustrated, said construction permitting of being varied within the scope of the appended claims.

What I claim is:

1. An apparatus for imposing vibratory impacts upon fillings of tooth cavities, comprising a hand-piece, a reciprocable pin constructed and arranged to operate upon fillings of tooth cavities, a pair of members adapted to be forced against each other and rotatable relative to each other about the axis of said reciprocable pin, cooperating cams on said members for reciprocating said pin, one of said members being hollow and secured to said hand-piece, the other of said members having a rod connected thereto, said rod extending through said hollow member and detachably connected with said hand-piece, a drive

shaft mounted in said hand-piece, and means transmitting rotary movement from said drive shaft to said rod.

2. An apparatus for imposing vibratory impacts upon fillings of tooth cavities, comprising a hand-piece, a rotary and reciprocable pin constructed and arranged to operate upon fillings of tooth cavities, a pair of members adapted to be forced against each other and rotatable relative to each other about the axis of said reciprocable pin, cooperating cams on said members for reciprocating said pin, one of said members being hollow and secured to said hand-piece, the other of said members having a rod connected thereto, said rod extending through said hollow member and detachably connected with said hand-piece, a drive shaft mounted in said hand-piece, and means transmitting rotary movement from said drive shaft to said rod.

3. An apparatus for imposing vibratory impacts upon fillings of tooth cavities, comprising a hand-piece, a reciprocable pin constructed and arranged to operate upon fillings of tooth cavities, a pair of members adapted to be forced against each other and rotatable relative to each other about the axis of said reciprocable pin, cooperating cams on said members for reciprocating said pin, one of said members being hollow and secured to said hand-piece, the other of said members having a rod connected thereto, said rod extending through said hollow member and detachably connected with said hand-piece, said pin being rigidly connected with said other one of said members, a drive shaft mounted in said hand-piece, and means transmitting rotary movement from said drive shaft to said rod.

4. An apparatus for imposing vibratory impacts upon fillings of tooth cavities, comprising a hand-piece, a non-rotary reciprocable pin constructed and arranged to operate upon fillings of tooth cavities, a pair of members adapted to be forced against each other and rotatable relative to each other about the axis of said reciprocable pin, cooperating cams on said members for reciprocating said pin, one of said members being hollow and secured to said hand-piece, the other of said members having a rod connected thereto, said rod extending through said hollow member and detachably connected with said hand-piece, a drive shaft mounted in said hand-piece, and means transmitting rotary movement from said drive shaft to said rod.

5. An apparatus for imposing vibratory impacts upon fillings of tooth cavities, comprising a hand-piece, a reciprocable pin constructed and arranged to operate upon fillings of tooth cavities, a pair of members adapted to be forced

against each other and rotatable relative to each other about the axis of said reciprocable pin, cooperating cams on said members for reciprocating said pin, one of said members being hollow and secured to said hand-piece, the other of said members having a rod connected thereto, said rod extending through said hollow member and detachably connected with said hand-piece, a non-rotatable sleeve surrounding said pin and having means preventing rotary movement of said pin, a drive shaft mounted in said hand-piece, and means transmitting rotary movement with said drive shaft to said rod.

6. An apparatus for imposing vibratory impacts upon fillings of tooth cavities, comprising a hand-piece, a reciprocable pin constructed and arranged to operate upon fillings of tooth cavities, a pair of members adapted to be forced against each other and rotatable relative to each other about the axis of said reciprocable pin, cooperating cams on said members for reciprocating said pin, one of said members being hollow and secured to said hand-piece, the other of said members having a rod connected thereto, said rod extending through said hollow member and detachably connected with said hand-piece, resilient means tending to move said pin in one direction, said members and cams being constructed and arranged to move said pin in the opposite direction, a drive shaft mounted in said hand-piece, and means transmitting rotary movement from said drive shaft to said rod.

7. An apparatus for imposing vibratory impacts upon fillings of tooth cavities, comprising a hand-piece, a reciprocable pin constructed and arranged to operate upon fillings of tooth cavities, a pair of members adapted to be forced against each other and rotatable relative to each other about the axis of said reciprocable pin, cooperating cams on said members for reciprocating said pin, one of said members being hollow and secured to said hand-piece, the other of said members having a rod connected thereto, said rod extending through said hollow member and detachably connected with said hand-piece, a sleeve detachably connected with said hand-piece and surrounding said pin, members and cams.
